William S. Blunt INVENTOR

BY *A. Sidney Doane*

ATTORNEY

UNITED STATES PATENT OFFICE.

WILLIAM S. BLUNT, OF NEW YORK, N. Y., ASSIGNOR TO CATHARINE S. BLUNT, OF SAME PLACE.

STAND-FRAME FOR HOISTING.

SPECIFICATION forming part of Letters Patent No. 258,548, dated May 30, 1882.

Application filed April 28, 1882. (No model.)

To all whom it may concern:

Be it known that I, WILLIAM S. BLUNT, of the city, county, and State of New York, have invented, made, and applied to use an Improved 5 Stand-Frame for Hoisting and Lowering Barrels or Cargo, for Derricks, for Weighing-Machines, and other Purposes; and I do hereby declare that the following is a full, clear, and correct description of the same, reference being had 10 to the accompanying drawings, and to the letters of reference marked thereon, in which—

Figure 1 is a view of my improved stand-frame folded. Fig. 2 is a view of the same opened for use. Fig. 3 is a view showing in 15 detail the mode of manufacture.

In the drawings like parts of the invention are pointed out by the same letters of reference.

The nature of the present invention consists 20 in improvements in the construction of stand-frames for the purposes indicated, as more fully hereinafter set forth, the object of the invention being the production of a stand-frame that shall be compact, possess great strength, 25 and one that can be afforded at a low price to the consumer.

To enable those skilled in the arts to make and use my invention, I will describe the construction and operation of the same.

30 A shows a strong hollow rod, usually formed of iron pipe, having a screw-thread, *a*, cut on both ends of sufficient length to allow three T's, B, to be successively screwed upon it at each end, and these T's are screwed upon the rod 35 A, so that one thread is left between each T, and thus a free but firm, smooth hinge movement is secured for the entire upper part of the frame, the upper rod moving and each of the six T's moving separately and independently.

40 To the two extreme outside T's two upright tubes, C, of equal length are screwed in with right and left elbows E at the lower ends facing each other, and a bottom rod or tube, D, of the same length as the rod A is screwed into

these elbows E, binding the whole together 45 and forming the outside half of the frame. The inside half of the frame is similarly formed, two upright tubes, F, being screwed into the two next outside T's, and being connected and firmly braced at the bottom by a rod, G, sufficiently long to allow this second portion of the frame to be folded within the outside frame. The remaining T's are supplied with hooks or rings *b*, as may be required for supporting or swinging purposes. They have, with the outside T's or hinges, a free, firm, and independent movement, combining great strength in 50 all directions, with economy in use, as the screw-thread offers a much larger wearing-surface, and its V shape causes it to make its own 55 thread in wearing, while the frame is bound together with great strength.

To prevent the frame opening too far when in use, chains H are applied half-way up to divide the leverage upon the top hinge, and at 60 the same time assist the upright tubes in supporting a heavy weight or vertical strain.

The frame thus constructed will be found particularly useful for hoisting or lowering purposes and for weighing purposes, and the 70 suspension-points—the T's provided with the hooks or rings *b*—are placed where the frame affords the greatest vertical support.

Having now set forth my invention, what I 75 claim as new is—

In a stand-frame for hoisting or lowering purposes, the combination of the following elements: a screw-threaded rod, A, the T's B, the upright rods C and F, the right-hand and left-hand elbows, E, and the bottom rods, D 80 and G, the same being constructed and operating substantially as and for the purposes set forth.

WILLIAM S. BLUNT.

In presence of—

WILLIAM V. H. HICKS,
A. SIDNEY DOANE.
